UNITED STATES PATENT OFFICE.

GEORGE DAILEY, OF SAGINAW, MICHIGAN.

DESIGN FOR A SIGN-PLATE AND HANGER.

48,812.

Specification for Design.

Patented Apr. 4, 1916.

Application filed August 30, 1915. Serial No. 48,127. Term of patent 7 years.

To all whom it may concern:

Be it known that I, GEORGE DAILEY, a citizen of the United States, residing at Saginaw, in the county of Saginaw and State of Michigan, have invented a new, original, and ornamental Design for a Sign-Plate and Hanger, of which the following is a specification, reference being had to the accompanying drawing, forming part thereof.

Figure 1 is in perspective, Fig. 2 is an edge view of a sign plate and hanger, showing my new design.

I claim—

The ornamental design for a sign plate and hanger, as shown.

GEORGE DAILEY.
